(57) **CLAIM**

The ornamental design for a luggage, as shown and described.

DESCRIPTION

FIG. 1 is a front elevational view of a luggage showing my new design therefor;

FIG. 2 is a rear elevational view thereof;

FIG. 3 is a right side elevational view thereof;

FIG. 4 is a left side elevational view thereof;

FIG. 5 is a top plan view thereof; and,

FIG. 6 is a bottom plan view thereof.

The straps and top handle in all the figures are shown as environment only and form no part of the design.
